UNITED STATES PATENT OFFICE.

JAMES J. WOOD, OF BROOKLYN, NEW YORK.

ELECTRIC PROJECTOR.

SPECIFICATION forming part of Letters Patent No. 407,914, dated July 30, 1889.

Application filed October 1, 1888. Serial No. 286,919. (No model.)

To all whom it may concern:

Be it known that I, JAMES J. WOOD, of Brooklyn, Kings county, New York, have invented certain new and useful Improvements 5 in Electric Projectors, of which the following is a specification.

This invention relates to projectors used for concentrating by means of a concave mirror the rays of light from a focussing electric 10 arc lamp, and directing such rays in approximately parallel direction in order to project to a distance as intense a beam of light as possible. Such projectors are used as search-lights on board vessels and for military purposes, and as head-lights for locomotives and 15 steamboats.

Marine projectors or search-lights have been made wherein a focussing electric lamp is inclosed within a casing containing a parabolic mirror, said casing being hung on trunnions on a transverse axis, so that the beam of light projected from the mirror may be thrown either directly forward or swung upwardly or downwardly. The trunnion-bearings 20 form part of a U-shaped frame, the base-plate of which is mounted to swivel on a base which is fastened to the deck of vessel. By means of this swivel the projector may be rotated in order that the beam of light may be 25 caused to sweep the horizon.

My invention constitutes an improvement in the construction of such marine projectors, and is also in part applicable to head-lights wherein the projector-casing is mounted on a 30 base through the medium of a swivel, whereby it may be rotated in a horizontal plane.

My invention relates, chiefly, to improvements in the manner of connecting the conducting-cables or circuit wires or leads which 35 conduct the electric current to the arc lamp, the object of my invention being to so arrange these leads that they shall be out of the way, and consequently free from liability to accidental injury, and to prevent the twisting off of the leads by means of the rotation 40 of the swivel or pivot members of the projector.

My invention also comprehends other improvements, as will be fully hereinafter 45 described.

Figure 1 of the accompanying drawings is a front elevation of a marine projector or

search-light constructed according to my invention. Fig. 2 is a vertical transverse mid-section thereof, looking from the left-hand 55 side. Fig. 3 is a plan of the lower portion of the apparatus in horizontal section on the line 3 3 in Fig. 2, partly broken away. Figs. 4 and 5 are enlarged detail sections of one of the trunnion-connections of the projector-casing, each view being a section on the like-numbered line in the other. Fig. 6 is an enlarged sectional view of the switch or cut-out 60 on the front of the base cut in the plane of the line 6 6 in Fig. 2. Fig. 7 is a vertical 65 transverse mid-section of a head-light embodying part of my invention.

I will first describe the marine projector or search-light shown in Figs. 1 to 6, inclusive.

Let A designate the base, which is fastened 70 to the deck of the vessel or to other suitable foundation; B, the U-shaped carrying-frame mounted thereon and swiveled thereto; C, the projector-casing mounted on lateral trunnions borne by the frame B, and D, Fig. 2, 75 the focussing electric-arc lamp within the projector-casing. This electric lamp D is of peculiar construction, as will be apparent; but its construction is not claimed in the present application, being made the subject-matter 80 for another application for patent executed by me coincidently herewith. Its characteristic feature is the arrangement of the carbons in front of the regulator-casing, instead of above it, so that the arc is formed in front 85 of the casing and much lower down than was possible with the prior constructions of focussing-lamps. By means of this construction of lamp I am enabled to greatly reduce the size of the projector-casing, so that it need 90 not extend downwardly any farther than is necessitated by the size of the front or rim of the parabolic reflector E, whereas heretofore it has been necessary to construct the casing with a deep downward continuation or pocket, 95 extending a considerable distance beneath it, in which to place the regulator-casing of the focussing-lamp. My improved form of lamp not only avoids this disadvantage, but also, by bringing the greater portion of the weight 100 of the lamp mechanism to the rear of the reflector, it serves to counterbalance the weight of the reflector, instead of having itself to be counterbalanced by the fitting of idle coun-

ter-weights or ballast into the upper part of the projector-casing, as has heretofore been necessary.

For a further description of the construction of this improved lamp reference is made to my said application.

Except in the particulars herein described, the general construction of the apparatus, including that of the projector-casing, reflector, front glass, the rear door, the swiveled **U**-shaped frame and the base, is the same as in projectors of this character heretofore made, and does not require particular description.

The projector-casing has its trunnions (lettered *a* and *a'*) made hollow, the left-hand one *a* (on the right in Fig. 1) serving as a means for admitting the conducting wires or leads, as shown in detail in Figs. 4 and 5, and the one at the right (lettered *a'*) being utilized as a camera obscura in order to aid in adjusting the arc to the correct focus of the mirror, as heretofore, it being understood that the pivotal axis of the projector-casing intersects the focus of the reflector, as clearly shown in Fig. 2. The trunnion *a'* also is provided with an operating-handle *F*, Fig. 1, the metal boss of which embraces it and is clamped firmly to it, so that by turning the handle the projector-casing, which is nicely balanced, may be turned with ease to any inclination. A set-screw *c'* is provided for clamping the trunnion, in order to hold the projector rigidly at any angle. The projector-casing is so balanced that its center of gravity is very slightly below its pivotal axis, so that after having been deflected it will upon being released return automatically to a level.

The **U**-shaped frame *B* consists of a circular or disk-shaped bottom plate *b* and two curved arms *c c*, projecting outwardly and upwardly therefrom and formed at their upper ends with the bearings *d d* for the trunnions *a a'*. The bottom plate *b* rests upon a corresponding disk or plate *e*, forming the top of the boss *A*, as best shown in Fig. 2. The central portion of this top plate projects upwardly in the form of a tubular boss *f*, which forms a loose fit with a hub or bearing-boss at the center of the bottom plate *b*, a nut *f'* being screwed on the projecting end of this boss to confine the bottom plate *b* down in place against the top plate *e*. The construction thus described constitutes a swiveled connection between the frame *B* and the base *A*. This swivel I will designate by the letter *G*.

On the base *A*, and preferably on the front thereof, is mounted a cut-out or electric hand-switch *H* for short-circuiting and thereby extinguishing the lamp. The construction is best shown in Fig. 6, where *I I'* are the respective positive and negative binding-posts, to which the terminals of the external circuit-wires are to be connected, and which are fixed to metal plates *g g*, which are fastened to the cast-iron shell of the base *A* by means of screw-bolts *l l*, as clearly shown, being in-

sulated from the base. A metallic switch-plate *J*, having a handle *j* fixed to it, is pivoted at one end to a plate *i*', which is integral with, or in metallic contact with, the binding-post *I*', and at its other or free end the switch-plate may, when moved to the proper position, as shown in Fig. 6, enter a notch or recess in a plate *i*, which is integral with or in metallic connection with the binding-post *I*. This switch-plate *J* will thus form a short circuit between the two binding-posts, thereby cutting out the lamp. In Fig. 1 this switch-plate is shown thrown down, so as to bring the lamp in circuit.

The respective conducting cables or leads *K K'* are connected the one to the positive and the other to the negative binding-post by being clamped between plates *t t'*, which are fastened by the screws *l l* on the inside of the base *A*, the screw-threads engaging the plate *t*'. They are thence carried out through the hollow pivotal boss *f* of the swivel *G*, on emerging from which they pass up along one of the arms *c* of the **U**-shaped frame *B*, being fastened into the angles formed by the junction of the rib and web of this arm, and thereby brought out of the way, where they are protected from injury. They are fastened at intervals by pins *v v*, which are driven tightly into holes drilled transversely through the rib of the arm *c*, leaving both ends projecting, and these projecting ends are bent down to embrace the cables. At the top of the arm the cables pass off at either side, and, being looped around the exterior of the trunnion-bearing, are thence carried in through the hollow trunnion *a* to the interior of the projector-casing *C*, wherein they are led to the binding-posts on the top of the regulator-casing of the electric lamp. It will thus be observed that the leads are carried through the pivotal axis of the rotative joints or connections in both the swivel *G* and the trunnion *a*, so that in the case of any rotative movement of either of these parts the only disturbance of the cables is the slight twist thereby imparted to them, which is practically insignificant.

The cables are quite out of the way and protected against accidental injury, being so arranged that they cannot foul either with the person of the operator or with any of the appurtenances about the deck of a vessel. There is hence no danger of their being accidentally torn or broken, and thereby causing the formation of an arc which might occasion a fire.

The only danger to which the cables are subject is that of being twisted off by the undue continuance of the rotative movement imparted either to the swivel *G* or trunnion *a*. To prevent the possibility of this, I provide stops on the respective rotative parts, which by their abutment limit the rotative movement, and thereby prevent the rotation in any one direction being continued so far as to rupture the cables. In the construction

shown these stops are so arranged as to prevent more than half a revolution in either direction from the normal position of the apparatus; but in case a greater or less range 5 of movement is preferred this limit may be varied by a corresponding change in the arrangement or construction of the stops.

The stops for limiting the rotative movement in a horizontal plane consist of a lug or 10 projection *m* on the under side of the plate *b* and an upwardly-projecting lug *n* on the upper side of the plate *e*, the two being relatively arranged so that one shall come into the path of the other upon the rotation of the 15 swivel, and being arranged at diametrically-opposite sides when the apparatus is in the normal position, as clearly shown in Figs. 2 and 3. Upon the rotation of the frame *B* in either direction the stop *m* will, upon the completion 20 of approximately half a revolution, strike the stop *n* and thereby arrest the movement. With the construction shown the sweep of the projector in a horizontal plane is an entire revolution, less only the angular thickness 25 of the two stops *m n*. In practice for ship use the stops are so arranged that they come into play when the axis of the light is turned aft, and the projector being arranged on the central line of the vessel and forward 30 of the masts and smoke-stacks, the inability to make a complete revolution is practically no disadvantage, since the axis of the beam of light can be thrown so nearly directly aft as to be partially intercepted by the masts or 35 smoke-stacks, and there would obviously be no advantage in being able to direct the light aft against the middle of the masts or stacks; hence all the available horizon can be swept with the projector constructed as shown. A 40 similar arrangement of stops is applied to the trunnion *a*, as shown in Figs. 4 and 5, where *p* designates the lug or wing cast on the trunnion, and *q* designates the lug or wing cast on the bearing *d* of the trunnion. These stops 45 will not abut until the projector-casing is swung so far on the trunnions as to be inverted and direct the light backward—a limit which is beyond that which is necessary in the practical use of the light. The stops are 50 chiefly useful to prevent the projector-casing being swung around the wrong way after being turned up for cleaning, thereby unduly twisting the cables.

In order to adapt the search-light for use 55 as a head-light, for which purpose the beam of light should be thrown directly forward in an invariable direction, I provide a lock or catch for holding the swivel *G* rigid in the normal position, the projector-casing being held rigid 60 by means of its set-screw *c'*. This lock may be variously constructed, one example of which is shown in Figs. 2 and 3, where a locking-lever *L* is pivoted to the rear of the base *A*, with its upper end engaging a notch *r*, 65 formed in the periphery of the plate *b*, and the lower end of the lever projecting downwardly and outwardly into position to be op-

erated by pressing the foot against it in order to release the lock. The lever is normally pressed out by a leaf-spring *s* beneath it, and 70 its upper arm is steadied by entering between lugs *r' r'*, which resist the transverse strain in case an effort is made to turn the swivel while it is locked. When it is desired to sweep the horizon with the search-light, the 75 operator will press with his left foot against the lever *L*, thereby releasing the lock, whereupon he can turn the projector to any desired position by means of the operating-handle *F*.

Fig. 7 shows my invention applied to an 80 electric head-light suitable for locomotives and for ships. In this figure the lamp is omitted, being the same as in Fig. 2. In this construction the frame *B* of the preceding figures is omitted, the projector-casing *C* being 85 mounted directly on the base *A*, and connected thereto through the medium of a swivel *G*, so that it may be rotated in either direction in order that the rear of the casing may be made accessible, it being usual to arrange 90 head-lights close in front of some obstruction, such as the smoke-stack in the case of a locomotive head-light. As the lamp is trimmed and adjusted through the door in the rear, the importance of this swiveling of the casing 95 whenever there is any obstruction directly behind the head-light is manifest. The leads *K K'* pass from the base *A* up into the casing *C* through the hollow pivotal boss *f* of the swivel, and the swivel is provided with stops 100 *m n*, as before described, to prevent undue twisting of the wires. Normally the lock *L* holds the head-light in place and keeps it from turning on the swivel. This lock is constructed of a spring-bolt carried by one member 105 of the swivel and its end entering a socket in the other member, an exterior knob being applied by which to operate the bolt.

Fig. 8 shows an improved means which I have devised for supporting the parabolic reflector within the projector-casing. Difficulty 110 has been found in adjusting the reflector so as to bring its focus exactly into the pivotal axis of the projector-casing when the latter is hung on trunnions, or into exact position relatively to a camera obscura at the side in the case of a head-light projector, such as is shown in Fig. 7. To facilitate this adjustment, I mount the reflector in the casing by means of brackets, which engage by means of screw-clamps the periphery of the reflector, and are thus adjustable relatively to the casing in longitudinal direction. This enables the reflector to be first placed with its focus on the proper line and subsequently fastened 115 in position by adjusting the brackets to it and clamping them in place in the casing. In the construction shown four brackets are employed, one of which (lettered *w*) is shown in Fig. 2 in oblique elevation, and on a larger scale in Fig. 8 in longitudinal section. This bracket consists of an L-shaped plate with a slot in one arm engaged by a screw *x*, passing through the projector-casing and screw-

ing into a nut, which is held from turning by being confined in a longitudinal recess or guideway on the inner side of the bracket. The front of the reflector is flanged outwardly, 5 and the flange is clamped to the front of the other arm of the bracket by means of a screw y. Sufficient freedom of motion is allowed at both the screws to permit of the requisite adjustment for compensating for any variations 10 that may occur in practice in the dimensions and focal points of different reflectors.

I claim as my invention the following defined novel features, substantially as hereinbefore specified, viz:

- 15 1. The combination, with a projector-casing, of a base supporting it and a swivel-joint between the base and casing having an axial opening, an electric lamp within the casing, and the circuit-leads thereof passing from the base through the axial opening in the swivel and into the casing, and stops on the respective members of the swivel adapted to limit the rotation of the casing on the base, and thereby prevent the excessive twisting of the 25 leads.
2. The combination, with a projector-casing, of a base supporting it and a swivel-joint between the base and casing having an axial opening, and stop projections on the respective members of said swivel located normally 30 diametrically opposite one another, whereby the rotation of the casing on the base is limited to half a revolution in either direction.

3. The combination of a projector-casing hung on trunnions, one of which is tubular, 35 a supporting-frame having bearings for said trunnions, and stops to limit the rotation of the casing on said trunnions, with the circuit-leads entering the casing through said tubular trunnion.

4. The combination, with a projector-casing and reflector therein, of a fastening for the reflector, consisting of clamping-brackets engaging the periphery of the reflector at intervals around its circumference and connected to the casing through the medium of a longitudinally-sliding connection, whereby the adjustment of the reflector to the proper focal position within the casing is facilitated.

5. The combination, with a supporting 50 frame formed with a web and rib, of conducting-leads traversing said frame and arranged in the angles at the junction of the web and rib, and a fastening therefor consisting of pins fixed in transverse holes in said rib and their 55 ends bent over and embracing the conductors.

In witness whereof I have hereunto signed my name in the presence of two subscribing witnesses.

JAMES J. WOOD.
